UNITED STATES PATENT OFFICE.

EDWARD D. FELDMAN, OF ALBANY, NEW YORK, ASSIGNOR TO PENCIL MECHANISM CORPORATION, A CORPORATION OF NEW YORK.

STEP-BY-STEP LEAD PENCIL.

Application filed October 23, 1922. Serial No. 596,309.

This invention relates to step-by-step lead pencils and in its more specific aspects to magazine lead pencils.

An object of the invention is to provide a 5 step-by-step lead pencil which is simple, sturdy and permanent in construction, which may be operated with ease and certainty, and which is economical of manufacture and assembly.

10 Another object is to provide an improved pencil of the general type disclosed in the co-pending applications of Alfred Woelm, Serial No. 588,688, filed September 16, 1922, and the division thereof, Serial No. 180,000, filed March 31, 1927.

Another object is to provide a step-by-step lead pencil of the continuous feed type, wherein the lead is gripped and propelled efficiently by spring-pressed grippers.

20 Another object is to provide an improved magazine lead pencil of the step-by-step type.

Other objects of the invention will in part be obvious and will in part appear hereinafter.

25 The invention accordingly comprises an article of manufacture possessing the features, properties, and the relation of elements which will be exemplified in the article hereinafter described and the scope of the application of which will be indicated in the claims.

30 For a fuller understanding of the nature and objects of the invention reference should be had to the following detailed description 35 taken in connection with the accompanying drawing, in which:—

Fig. 1 is a longitudinal section through a magazine pencil constructed in accordance with my invention.

40 Fig. 2 is a longitudinal section, at right angles to the section shown in Fig. 1, through the casing, and part section through the feeding mechanism.

45 Fig. 3 is a detail of the lead tube of my improved pencil.

Fig. 4 is a longitudinal section through the sleeve to which are pivoted the lead gripping and pushing jaws of the mechanism.

50 Fig. 5 is a side elevation of the feeding mechanism, illustrating a modified form of tension adapted to retard motion of the sleeve

at the beginning of either the upward or downward movement thereof.

The same reference characters refer to the same parts throughout the several views. 55

The invention is exemplified as embodied in a step-by-step magazine lead pencil. In the present exemplification there are provided a pair of tubular members, 2, and, 3, which together provide the casing for the pencil. 60

The lower casing member, 2, is tapered at its lower end, 15, so as to provide a tip portion having a restricted opening, and the upper casing member, 3, is formed to provide a magazine in which leads may be retained and from which leads may be fed toward the tip. 65

In the present instance, the lower end of the upper casing member, 3, is reduced slightly in diameter so as to fit closely but slidably within the upper portion of the lower casing member. 70

At the upper end of the member, 3, there is provided a cap, 4. If desired, there may be inserted in the portion, 3, a removable tubular member, 5, which may serve to provide a supplemental magazine portion from 75

which lead may be fed downwardly. In certain instances, the opening at the bottom of this member may be closed to permit the member to be used to hold a reserve supply of leads from which the lower magazine portion 80 may be manually refilled, or the member, 5, may be omitted altogether. When leads of a length substantially greater than one-half the length of the magazine portion provided by the magazine portion of the upper casing, 3, are procurable, it is ordinarily preferable to omit the member, 5. Moreover the member, 5, may be omitted if the length of the casing member, 7, is reduced so as to provide a shorter pencil. 85

90 As will be seen from Fig. 1, the pencil may be equipped with an eraser, 6, fitted into an eraser socket, 7, which may be inserted in the upper end of the member, 5, if desired.

95 In the present instance there is provided a central lead guide tube, 10, which is provided with an enlarged opening at its upper end, as illustrated at 11, and with an opening at its lower end, as indicated at 12, which is restricted for a portion of the length of the 100 tube so as to center the leads as they pass therethrough. Preferably, also the discharge

end is further restricted and is formed with longitudinal slits so as to provide resilient fingers which will grip the leads as they are forced through. The reduced diameter portion, 12, of the guide tube insures the proper alignment of an advance lead, 9^a, so that when a succeeding lead, 9^b, is forced downwardly it will press this lead against the top of the preceding one so as to overcome any tendency of the leads to break or to bring about a jamming of the pencil mechanism.

In order to permit the gripping and propulsion of a lead within the guide tube, the tube may be suitably slotted, there being provided in the present instance a pair of diametrically opposed longitudinal slots through which longitudinally movable gripping jaws, 24, extend.

The tube, 10, has fastened to its top, so as to form a continuation thereof, a cap member, 17, against the under side of which rests the upper end of the spiral spring, 18. The member, 17, forms the bottom of the reservoir for the leads, and central therein is an opening adapted to pass the leads, 9, the upper end of said opening being enlarged so as to form a crater with inclined sides. The surface, 19, of the member, 17, beyond the rim of the crater is gradually depressed as the outer edge of the surface is approached; the depressions being preferably such as will form a slight curve, as illustrated in the drawings. This form of top, i. e., depressed beyond the edge of the crater instead of level, or raised, tends to separate the leads in the magazine and prevent their crowding toward the center when the pencil is held in a vertical position so as to permit one of the leads in the magazine to drop through the opening in the member, 17, into the tube, 10, when it will be in position to be acted upon by the jaws, 24. The separating action of this form of top adds very greatly to the ease with which a lead from the magazine is introduced into the central tube, 10, of the feeding mechanism of the pencil, and provides for certainty of operation.

Fastened to the lower portion of the tube, 10, at a point below the slots, 13, by screw threads or other suitable means, is an anchor member, 14, adapted to fit snugly in the lower portion of the casing section, 2. The member 14, is provided with screw threads or other suitable means whereby the pointed member, 15, may be screwed into or otherwise fastened to the same.

The member, 15, is provided with a shoulder, 16, adapted to contact with the lower end of the portion, 2, of the casing. The end of the portion, 2, the anchor member, 14, and the pointed member, 15, are so proportioned that when the member, 15, is fastened into the member, 14, the portion, 2, of the casing will be forced against and held in intimate contact with the member, 14.

Mounted upon the central tube, 10, and capable of a limited longitudinal motion thereon, is the sleeve, 20, provided with diametrically opposed longitudinal slots flanked by projecting ears 22, 22, and between these ears are pivoted, at 23, the double armed levers, 24, which are the jaws which grip and actuate the leads.

Mounted upon the sleeve, 20, and capable of a limited longitudinal motion thereon, is a gripper-operating collar, 26, the upper end of which is in contact with the lower end of the spring, 18, which is always partially compressed and tending to force said collar downward. The inclined surface, 27, formed on the lower side of the collar, 26, will thus be forced in under the upper arms of the double armed levers or jaws, 24, and tend to force them away from each other, while the lower ends of said levers will be forced toward each other until they grip the lead. The portion of the jaws which contact with the leads are preferably toothed substantially as illustrated.

The collar, 26, is attached to the lower end of the portion, 3, of the casing by any suitable means which will provide for a limited amount of lost motion longitudinally. In the drawing this connection is illustrated as consisting of pins, 29, working in openings, 28, formed in the portion, 3.

When assembled as illustrated and described, the members, 2, 10, 14, 15 and 17, will move in unison and without appreciable lost motion between the parts; the magazine portion of the casing, 3, the collar, 26, and the sleeve, 20, with the parts attached thereto, though fastened together do not at all times move in unison.

To obtain the proper sequence in the movement of the parts of the feeding mechanism, it is necessary that the first part of the motion of the collar, 26, in either direction, shall not be accompanied by a movement in the same direction of the sleeve, 20, and the parts attached thereto. To insure the proper relative movements of the collar, 26, and sleeve, 20, there are provided in the modification exemplified in Fig. 5 a split spring, 36, working against a pin, 35, so as to provide a spring tension to retard the initial movement of the sleeve, 20, in either direction.

My preferred method of accomplishing the desired extra tension to produce a retard against the initial movement of the sleeve, 20, in either direction, is illustrated in Figs. 2 and 3. I form on the outer surface of the central tube, 10, at a point between the ends of the longitudinal slots, an annular projection, 31, and on the inner surface of the sleeve, 20, a pair of annular grooves, 32, 32, so spaced and positioned that the projection, 31, on the tube, 10, will be in alignment with one of said grooves at or very near the end of the upward and downward travel of the

- 11 sleeve. By making the width of the grooves, 13, in the tube, 10, somewhat greater than the thickness of the jaws, 24, the resilience of the sides of the tube may in certain instances be
 5 utilized to produce a spring action to retard the initial movement of the sleeve in either direction. This eliminates the necessity for supplying a spring such as the spring, 36, illustrated in Fig. 5 of the drawings.
- 10 In order to insure the desired separating movement of the lower ends of the jaws, 24, when the upper ends thereof are released from the wedging action of the inclined surface, 27, on the collar, 26, I utilize a U-shaped
 15 spring, 25, so shaped that the normal tendency thereof is to cause the jaws to separate and move out of engagement with the lead. This form of spring gives a very satisfactory action and is much simpler and less expensive
 20 than the springs made use of by Woelm.
- The manner in which my improved pencil operates is as follows, reference being had to Figs. 1, 2 and 4 of the drawings:
- 25 The portion, 2, of the casing being firmly held, when force is exerted tending to draw the portion, 3, of the casing out of the portion, 2, the first part of such a withdrawing movement will take up the lost motion between the pins, 29, in the collar, 26, and the
 30 lower edge of the openings, 28, in portion, 3. As soon as this lost motion is taken up, further withdrawal movement of the portion, 3, will carry upward the collar, 26, and cause further compression of the spring, 18. This
 35 initial movement of the collar, 26, will cause no movement of the sleeve, 20, and the parts attached thereto, but will release the wedging action of the surface, 27, against the upper ends of the jaws, 24, and permit the spring, 25, to withdraw the jaws from contact with the lead. After this has been surely accomplished, the collar, 26, will come into contact with the collar, 21, on the sleeve, 20, and the further movement of the portion, 3, will then
 40 also force upward the sleeve, 20, until the collar, 21, comes into contact with the bottom of the portion, 17, which is designed to act as a limiting stop for the withdrawal movement, unless destructive force is applied.
- 45 50 The force tending to separate longitudinally the two parts of the casing being withdrawn, the tension of the compressed spring, 18, will return the parts to their original relative positions, except for the lost motion between the pins, 29, and the edge of the holes, 28. This lost motion is provided so that the moving parts of the mechanism may follow up to grip a lead which may be under the standard diameter.
- 55 60 When the separating force is removed, the action of the spring, 18, first forces the inclined surface, 27, of the collar, 26, between the upper ends of the jaws, 24, thus forcing the lower ends thereof into contact with the lead at a point higher up than the point at
 65 which they previously moved out of contact therewith; the jaws then offer resistance to the further downward motion of the collar, 26, and the pressure on the spring, 18, continuing, the "retard" is overcome and the
 70 sleeve, 20, and the parts attached thereto, plus the lead against which the jaws are being forced by the action of said spring are carried downward until the sleeve, 20, reaches the lower limit of its possible travel. The
 75 movement of the sleeve and the parts attached thereto will then cease, but the tension of the spring, working through the collar, 26, and double ended levers or jaws, 24, will continue to exert a gripping action against the lead
 80 and so hold it firmly in place.
- I claim:
1. In a magazine lead pencil, the combination of a tubular casing in two parts one slideable within the other, the upper part of the
 85 casing forming the outer wall of a magazine adapted to contain a plurality of lead strips, the lower part pointed to provide a discharge opening and having mounted centrally there-
 in a slotted guide tube whose upper end forms
 90 the bottom to said magazine, a mounting recipro-
 95 cipable on said guide tube, lead-gripping members pivoted in said recipro-
 96 cipable mounting, means attached to said upper casing part for causing said gripping members to grip
 a lead strip in said guide tube, a spring normally causing said means to actuate said grippers, and a spring tending to release the grip
 of said gripping members.
2. In a magazine lead pencil, a space adapt-
 ed to contain a plurality of strips of lead, the bottom wall of said space having a hole therethrough; a crater with inclined sides leading downward toward said hole, said
 100 bottom wall slanting downward and away from the rim of said crater.
3. In a feeding mechanism for a lead pen-
 cil, a guide tube adapted to guide a lead into said feeding mechanism, a slot in said guide tube, and a projection formed on the outside
 105 thereof: a sleeve slidably mounted on said
 110 guide tube, and grooves formed on the inside of said sleeve, the projection on said guide tube adapted to enter one of the grooves in
 115 said sleeve when it is brought into alignment therewith.
4. A guide tube for guiding leads from the magazine of a mechanical pencil to the delivery point thereof, and consisting of a tube of suitable material the upper and major portion of which has a bore the minimum diameter of which is considerably greater than that of the lead to be guided, and in the walls of which are longitudinal slots adapted to pass and permit reciprocal movement there-
 120 in of the grippers which form a part of the
 125 pencil mechanism; the lower and remaining portion of the tube contracted to and having a substantially uniform inner diameter but slightly greater than the diameter of the lead
 130

to be guided, the lower end of the tube slotted to form a plurality of fingers the free ends of which are rolled inward until the opening therethrough is slightly smaller than the lead 5 to be guided.

5. A guide tube for guiding leads from the magazine of a mechanical pencil to the delivery point thereof, and consisting of a tube of suitable material the upper and major portion of which has a bore the minimum diameter of which is considerably greater than the diameter of the lead to be guided, and in the walls of which are longitudinal slots adapted to pass and permit reciprocable movement 10 therein of the grippers which form a part of the pencil mechanism; the lower portion of the tube contracted and having a substantially uniform internal diameter for most of its length and but slightly greater than the 15 diameter of the lead to be guided; said tube having an annular rib on the outside thereof adapted to enter a slot in the lead gripping and feeding mechanism of the pencil when said mechanism reaches its limit of travel.

20 6. In a step-by-step lead pencil, the combination of means providing a tip at the lower end of the pencil, a member at the upper end of the pencil arranged for longitudinal movement with respect to said tip, a plurality of 25 rockingly mounted lead-gripping and -feeding jaws, and means responsive to the reciprocation of said longitudinally movable member to reciprocate said jaws and to cause the same to feed a lead step-by-step through the 30 pencil.

7. In a step-by-step lead pencil, the combination of upper and lower casing members and lead-feeding mechanism including a plurality of rockingly mounted lead-gripping 40 jaws, said upper and lower casing members being arranged for relative longitudinal movement, and said lead-feeding mechanism being arranged to cause an operation of said jaws for feeding the lead step-by-step through 45 the pencil in response to the relative reciprocation of said casing members.

8. In a step-by-step magazine lead pencil, the combination of a casing member, a perforated plate-like member secured thereto, a 50 tubular member reciprocable with respect to said casing member and cooperating with said plate-like member to provide a lead magazine, and lead-gripping and -feeding mechanism operable in response to the reciprocation of 55 said tubular member to feed a lead step-by-step through the pencil.

9. In a step-by-step magazine lead pencil, the combination of a casing member, a perforated plate-like member secured thereto, a 60 tubular member reciprocable with respect to said casing member and cooperating with said plate-like member to provide a lead magazine, a plurality of longitudinally movable lead-gripping jaws, and mechanism operable

in response to the reciprocation of said tubular member to reciprocate said jaws and to cause the same to grip and release a lead to propel the lead step-by-step through the pencil.

10. In a step-by-step magazine lead pencil, the combination of a pair of telescoping casing members, a reciprocable spring-controlled gripping and feeding device normally gripping a lead and adapted to be actuated by the displacement of a part of said casing in opposition to the controlling spring, and means whereby excess pressure applied against the lower end of the lead will cause said lead and said gripping and feeding device to move upward within said casing and 75 to be returned to normal position when said excess pressure is removed, said lead-gripping and -feeding device comprising a plurality of lead-gripping jaws.

11. In a pencil mechanism, the combination of an anchor piece arranged to be detachably secured to a pencil casing, a plate adapted to serve as the bottom of a lead magazine, means detachably to secure said bottom plate to said anchor piece, a reciprocable member, and means responsive to the reciprocation of said reciprocable member to propel a lead step-by-step through the pencil.

12. A magazine lead pencil comprising a tubular casing, an anchor piece, means detachably to secure said anchor piece within said casing, a tubular member reciprocable within said casing, a bottom plate cooperating with said tubular member to provide a lead magazine, said bottom plate being detachably secured to said anchor piece, a reciprocably movable lead-gripping unit between said plate and said anchor piece, and means carried by said inner tube for operating said lead-gripping unit.

100 13. In a magazine pencil comprising an outer shell and a tubular member reciprocable within said shell, the combination of an anchor piece secured in the bottom of said shell, a bottom plate cooperating with said tubular member to provide a lead magazine in the upper end of the pencil, and a member extending downwardly from said bottom plate to said anchor piece, said anchor piece and said member being formed with means 110 for detachably securing said plate on said anchor piece, and means beneath said plate to propel lead through said anchor piece in response to the reciprocation of said tubular member.

115 14. In a step-by-step lead pencil, the combination of a longitudinally movable member, a plurality of longitudinally movable lead grippers, a spring-controlled member adapted to cause lead-gripping and -feeding operations of said grippers in response to the operation of said longitudinally movable member, and means providing a lost mo-

- tion connection between said longitudinally movable member and said spring-controlled member.
15. In a step-by-step magazine lead pencil, the combination of a tubular casing in two parts, one slidable within the other, means to provide in the upper part of said casing a magazine space adapted to contain a plurality of leads, means to provide a discharge opening in the lower end of the lower part of the casing, means providing a passageway opening into the bottom of said magazine whereby a lead will automatically drop into said passageway whenever the rear end of the lead therein passes below the entrance thereto, a spring-controlled lead-gripping and -feeding unit reciprocable in said casing intermediate said magazine and said discharge opening, the controlling spring of said unit resisting longitudinal displacement of the parts of said casing, and means whereby the longitudinal displacement of a part of said casing, first in opposition to, and then under the urge of said spring, will impart a reciprocating movement and lead-releasing and -gripping actions to said mechanism whereby a lead will be fed step-by-step through the pencil. 70
16. In a step-by-step magazine lead pencil, the combination of telescoping upper and lower tubular casing members, means to provide a lead magazine in the upper casing member, means to guide a lead downwardly from said magazine to the lower end of the pencil, a reciprocable lead-gripping unit including a plurality of lead-gripping jaws, normally gripping a lead in transit from the magazine to the lower end of the pencil, and means comprising a spring-controlled member adapted to cause lead-gripping and -feeding action of said gripping unit in response to the relative longitudinal displacement of said casing members whereby the lead will be fed step-by-step through the pencil. 80
17. In a step-by-step pencil, means providing a pencil tip, a member movable longitudinally with respect to said tip, a lead-gripping unit including a plurality of grippers, yieldable means for reciprocating said lead-gripping unit in response to the reciprocation of said longitudinally movable member, means to cause said grippers alternately to grip and release a lead in the pencil at predetermined points in their cycle of movement for propelling a lead step-by-step toward and out of said tip, and resilient means for momentarily delaying the reciprocation of said grippers. 90
18. In a step-by-step lead pencil, the combination of telescoping upper and lower casing members, a plurality of rockingly mounted grippers connected with the upper casing member, means normally to maintain said gripper in gripping engagement with a lead 100
- in the pencil, and means to cause said grippers to release the lead, move upwardly, regrip the lead at a higher point, and move downwardly in response to an upward movement of the upper casing member. 105
19. In a step-by-step lead pencil, the combination of a plurality of longitudinally movable pivotally mounted lead-grippers, a spring connecting said grippers and tending to move the same out of engagement with a lead in the pencil, means normally overcoming the action of said spring, and means comprising an exteriorly accessible member to reciprocate said grippers and to render the previously mentioned means inoperative during at least a portion of the upward movement of said grippers. 115
20. In a step-by-step lead pencil, the combination of a plurality of longitudinally movable lead-grippers, a single spring tending to move said grippers out of engagement with a lead in the pencil, means normally overcoming the action of said spring, and means comprising an exteriorly accessible member to reciprocate said grippers and to render the previously mentioned means inoperative during at least a portion of the upward movement of said grippers. 120
21. In a step-by-step lead pencil, the combination of a plurality of lead-grippers, a spring-pressed member acting normally to cause said grippers to grip a lead for writing purposes, means forming a part of the pencil casing for moving said spring-pressed member against the pressure of its spring, means to move said grippers out of engagement with the lead, means to move the grippers upwardly along the lead, and means comprising said spring-pressed member to return the grippers to gripping position and to feed forward a lead. 125
22. In a step-by-step magazine lead pencil, the combination of a tubular member and a pencil tip mounted for relative movement, said tubular member being adapted to provide a magazine chamber for containing a plurality of leads arranged side-by-side, a lead-guiding tube adapted to guide leads successively from said magazine to said tip, said tube being connected with said tip and extending into said chamber whereby the relative reciprocation of the magazine chamber and the tip will agitate the leads in the chamber and facilitate the movement of leads from the chamber to the guide tube. 130
23. In a step-by-step magazine lead pencil, the combination of upper and lower tubular members, the upper tubular member being mounted for longitudinal movement, means including the upper tubular member to provide a lead magazine, a plurality of longitudinally movable grippers contained within the lower tubular member and adapted to grip a lead in transit from said magazine to the lower end of the pencil, a longi-

- tudinally movable gripper-operating member, and means including said gripper operating member to normally maintain said grippers in engagement with the lead, and, 5 when the gripper operating member is reciprocated in response to the longitudinal movement of said upper tubular member, to impart longitudinal movement of said grippers, and to cause said grippers to grip a lead 10 when the grippers are in an upward position and to release a lead when the grippers are in a downward position, whereby said grippers will grip and propel a lead step-by-step through the pencil.
- 15 24. In a step-by-step pencil, the combination of a casing member, a plurality of longitudinally movable lead-gripping elements, resilient means tending to spread said grippers, longitudinally movable gripper operating means arranged to normally maintain 20 said grippers in gripping engagement with a lead in the pencil and when reciprocated to impart longitudinal movement to said grippers and to press said grippers against the lead during the major portion of the 25 downward movement thereof, a longitudinally movable exteriorly accessible member extending above said casing member, and means providing a connection between said 30 actuating member and said gripper-operating means.
25. In a step-by-step magazine lead pencil, the combination of a casing member, a longitudinally movable tubular member, means including 35 said tubular member to provide a lead magazine in the upper part of the pencil, a plurality of longitudinally movable jaws adapted to grip a lead therebetween, a gripper-operating member connected with said 40 tubular member for imparting longitudinal movement to said jaws, and means including said gripper-operating member to cause said

jaws to grip and propel leads from said magazine step by step through the pencil.

26. In a step-by-step magazine lead pencil, 45 the combination of a casing member, a longitudinally movable tubular member, means including said tubular member to provide a lead magazine in the upper part of the pencil, a plurality of longitudinally movable jaws 50 adapted to grip a lead therebetween, a gripper-operating member, means providing a spring controlled lost motion connection between said tubular member and said gripper-operating member, and means including said 55 gripper-operating member to cause said jaws to grip and propel leads from said magazine step by step through the pencil.

27. In a step-by-step pencil, the combination of a lead-gripping and feeding unit, 60 means to reciprocate said unit and to cause the same to grip and release a lead, and means for retarding upward and downward movements of said gripping unit until releasing or gripping action has been imparted to the 65 unit, said means comprising a bifurcated spring fixed with respect to the casing and a pin on the gripping means to engage between the furcations of said spring.

28. In a step-by-step pencil, the combination of a lead-gripping and feeding unit, 70 means to reciprocate said unit and to cause the same to grip and release a lead, and means for retarding upward and downward movements of said gripping unit until releasing 75 or gripping action has been imparted to the unit, said means comprising a pair of springs fixed with respect to the casing and a pin on the gripping means to engage between the springs. 80

In testimony whereof I have affixed my signature.

EDWARD D. FELDMAN.
